INVENTOR:

FREDERICK PARKER,

By his Attorneys,

Benjamin Wright

UNITED STATES PATENT OFFICE.

FREDERICK PARKER, OF LONDON, ENGLAND, ASSIGNOR TO PARKER AND COMPANY (LONDON) LIMITED, OF LONDON, ENGLAND.

MEANS FOR WAVING HAIR.

Application filed August 31, 1925. Serial No. 53,678.

To all whom it may concern:

Be it known that I, FREDERICK PARKER, a subject of the King of Great Britain, residing at 4 and 5, Bridgewater Square, London, 5 England, have invented new and useful Improvements in Means for Waving Hair, of which the following is a specification.

It has before been proposed to wave hair by means of two combs frictionally held together by interlocking prongs and sockets.

10 This invention relates to improved means for holding together the combs.

According to this invention the two combs are provided with positive interconnecting 15 means.

One of the combs may be provided with two or more fastening members adapted to engage corresponding projections or studs on the other comb.

20 The fastening members may be formed of spring or any other suitable material and may be of the type ordinarily used to secure the hair in hair slides, or they may consist of rubber bands or one comb may be provided with arms, either pivoted or fixed, 25 having holes which engage pins on the other comb, which pins may be on the end pieces or sides of the comb.

To wave hair, the combs are inserted in 30 the hair whilst it is damp, one up and one down, and connected to one another. They are allowed to remain there until the hair is perfectly dry.

The invention is illustrated in the accompanying drawings in which Figures 1 to 4 35 show various forms of combs constructed in

accordance with this invention. Figure 5 is a sectional view of Figure 1 with the combs in position.

In the drawings *a* and *b* are two combs. 40

Referring to Figure 1 the comb *a* is provided with spring clips *c* hinged at *d* to the comb *a* and adapted to engage studs *e* on the comb *b* when in position.

In Figure 2 the comb *a* has holes *f* through 45 which pass rubber bands *g* that are used in place of the clips shown in Figure 1. When the combs are in position the rubber bands *g* are passed over studs *h* on the comb *b*.

In Figure 3 the comb *a* has arms *j* pivoted 50 at *k*. The other ends of the arms *j* are provided with holes *l* which engage spring studs *m* on the comb *b*.

In Figure 4 the outer teeth of the comb *a* have holes *n* that engage studs *o* on the outer 55 teeth of the comb *b*.

Figure 5 shows the combs *a* and *b* as in Figure 1 in position on the hair.

What I claim is:—

A comb comprising two bodily separable 60 toothed members of substantially the same size and shape with the teeth of one member interlocked with the teeth of the companion member, one of said members carrying hinged fastening devices at its opposite end 65 portions and the other member carrying studs with which said fastening devices engage.

In testimony that I claim the foregoing as my invention I have signed my name this 70 17th day of August, 1925.

FREDERICK PARKER.
